FURNACE DOOR

Charles A. Martin and John F. Farris,
Nashville, Tenn.

Application March 20, 1942, Serial No. 435,576

1 Claim. (Cl. 110—172)

The present invention relates to new and useful improvements in furnace or boiler doors, and has for its primary object to provide a device of this character comprising novel means for discharging a stream of air over the fire box in a manner to cause more complete combustion, thereby materially reducing or substantially eliminating smoke in addition to promoting efficiency and economy.

Other objects of the invention are to provide a door of the aforementioned character which is adapted to be expeditiously installed for operation on a conventional furnace or boiler front without the necessity of making material structural alterations therein.

Other objects of the invention are to provide a furnace or boiler door of the character described which will be comparatively simple in construction, strong, durable, highly efficient and reliable in use, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a furnace or boiler door constructed in accordance with the present invention.

Figure 2 is a view in horizontal section, taken substantially on the line 2—2 of Figure 1.

Figure 3 is a vertical sectional view, taken substantially on the line 3—3 of Figure 2.

Figure 4 is a vertical sectional view, taken substantially on the line 4—4 of Figure 1.

Figure 5 is a top plan view of the air manifold.

Figure 6 is a fragmentary view in elevation of one end portion of the air manifold.

Referring now to the drawings in detail, it will be seen that the embodiment of the invention which has been illustrated comprises a substantially oval body which is designated generally by the reference numeral 1, said body being of hollow metallic construction for providing a chamber 2. The body 1 is hingedly secured at one end, as at 3, for swinging movement in a horizontal plane on the usual front 4 of a conventional furnace or boiler. The hinge 3 permits limited vertical movement or play of the body 1. A suitable latch 5 is provided on the free end of the body 1.

Extending through the body 1 is a centrally located draft tube 6. A suitable damper 7 on the front of the body 1 controls the draft tube 6.

Extending through the body 1 and projecting into the opening 8 in the furnace front 4 is a plurality of bolts 9. Mounted on the inner end portions of the bolts 9 is a liner 10. Sleeves 11 on the bolts 9 space the liner 10 from the inner wall of the body 1.

The lower portion of the peripheral wall of the body 1 has formed therein a beveled opening 12. Extending between the opening 12 and the draft tube 6 in the body 1 is a substantially Y-shaped baffle 13. Mounted on the draft tube 6 is a pair of oppositely inclined baffles 14 which constitute what may be considered continuations of the branches or arms of the substantially Y-shaped baffle 13.

Projecting outwardly from the upper portion of the inner wall of the body 1, between the upper end portions of the baffles 14, is a discharge neck 15. The liner 10 has formed therein an opening 16 which accommodates the discharge neck 15. This is shown to advantage in Figure 4 of the drawings.

Secured on the furnace front 4, below the opening 8, is an air manifold 17 in the form of an elongated casing. On one end, the manifold 17 is provided with an intake neck 18 for connection with a suitable source of air. A horizontally slidably access door or plate 19 is provided on the other end of the manifold 17. Rising from this end portion of the manifold 17 is an outlet branch or neck 20 having a beveled upper end portion which is adapted to seat in the correspondingly shaped opening 12 in the body 1. In this manner a substantially air-tight joint or connection is had between the door and the air manifold when said door is in closed position.

It is thought that the operation of the device will be readily apparent from a consideration of the foregoing. Briefly, air from a blower or other source of supply enters the manifold 17 at 18 and is discharged upwardly into the chamber 2 of the door through the outlet branch 20 of said manifold. The upwardly flowing air is divided into two streams by the substantially Y-shaped baffle 13, said two streams of air flowing around the baffles 14 in a manner to approach and enter the outlet 15 from opposite directions. Thus, the upwardly flowing air encounters little resistance in passing the draft tube 6 and turmoil is kept at a minimum. The outlet 15 discharges the air into the furnace or boiler over the fire therein. By simply lifting the door sufficiently to clear the outlet branch 20 of the air manifold 17, said door may be readily swung to open position on the

hinge structure 3. There is enough looseness or play in the hinge structure 3 to permit this.

It is believed that the many advantages of a furnace or boiler door constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

In a furnace including a front having an opening therein, a horizontally elongated manifold mounted on said front below the opening, said

manifold having an air intake opening in one end, a slidable access door on the other end of the manifold, a discharge neck rising from the manifold, and a vertically movable hollow door hingedly mounted for horizontal swinging movement on the furnace front for controlling the opening therein, said door having an opening therein for the reception of the neck, said neck including a beveled free end adapted to seat in the door opening, the door further having a discharge opening therein communicating with the furnace.
